UNITED STATES PATENT OFFICE.

CHARLES A. RIGHTER, OF PHILADELPHIA, PENNSYLVANIA, ASSIGNOR TO JAS. & GEO. D. BROMLEY, OF SAME PLACE.

DESIGN FOR A CARPET.

SPECIFICATION forming part of Design No. 13,684, dated February 27, 1883.

Application filed January 20, 1883. Term of patent 3½ years.

To all whom it may concern:

Be it known that I, CHARLES A. RIGHTER, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—

The design for carpets, as herein shown and described.

Witnesses: CHAS. A. RIGHTER.

FRANK B. BIRCH,
GEO. S. McGONIGLE.
